SAILING AND STEERING RIG FOR ATTACHMENT TO FLAT BOTTOM RUBBER BOATS OR RAFTS

John C. Boyd, Riverside, Calif.

Application November 21, 1947, Serial No. 787,328

2 Claims. (Cl. 9—2)

1

My invention relates to a rig or attachment to be installed upon flat bottomed rubber boats or rafts, or like devices.

An important object of the invention is to provide a rig of the above mentioned character which will render it possible to satisfactorily sail such flat bottomed boats or rafts, and also render it easy to accurately maneuver the same when rowed or paddled.

A further object of the invention is to provide a rig of the above mentioned character, formed of assemblies which may be knocked down for the purpose of shipment, and opened and readily applied to the boat or raft.

In the drawings,

Figure 1 is a side elevation of a rig embodying my invention as applied to a flat bottomed rubber boat,

Figure 2 is a front end elevation of the same,

Figure 3 is a side elevation of the base or floor assembly,

Figure 4 is a bottom plan view of same,

Figure 5 is a side elevation of same, showing it partly folded,

Figure 6 is a perspective view of the keel, showing the same partly folded,

Figure 7 is a detailed section taken on line 7—7 of Figure 4,

Figure 8 is a detailed section taken on line 8—8 of Figure 6.

Figure 9 is a side elevation of the rudder and associated elements,

Figure 10 is a horizontal section taken on line 10—10 of Figure 9, and

Figure 11 is a detailed section through a socket which receives the mast.

Figure 12 is a fragmentary rear elevation showing the rudder and stern section of the boat.

In the drawings, the numeral 15 designates a flat bottomed rubber boat, of the type that can be inflated for use. This boat may be of the general type shown in Patent 2,370,069. The boat 15 has a flat bottom and is not equipped with a keel.

The numeral 16 designates the base or floor assembly or unit, comprising a bow unit or section 17, an intermediate section 18, and a stern section 19, see more particularly Figure 4. Streamlined blocks 20 are rigidly mounted upon the lower face of the bow section 17, and companion streamlined blocks 21 are rigidly mounted upon the lower face of the intermediate section 18, and leaf-hinges 22 connect the pairs of blocks 20 and 21, and are arranged beneath them, as shown. The intermediate section 18 is

2

adapted to break downwardly with relation to the bow section 17. The stern section 19 is connected with the intermediate section 18 by leaf-hinges 23, secured to the upper faces of the sections 18 and 19, Figure 3, and the stern section 19 is adapted to break upwardly with respect to the section 18, Figure 5. The base or floor 16 is provided with a sub-keel 24, formed in separate sections 25, 26 and 27, rigidly mounted upon the lower faces of the bow section 17, the intermediate section 18, and the stern section 19, respectively. The sub-keel sections are arranged in end-to-end relation and form in effect a continuous sub-keel. Apertured cleats 28 and 29 are rigidly secured to the bow section 17, apertured cleats 29 rigidly secured to the intermediate section 18, and apertured cleats 28 and 29 rigidly secured to the stern section 19. All of the cleats are mounted upon the lower faces of the base or floor sections and project beyond the marginal edge of the same. The cleats 28 have their inner ends angularly arranged and apertured, Figure 7.

The base or floor 16 is arranged beneath the flat bottomed boat 15, with the bow section 17 next to the bow of the boat 15, and the base is secured to the boat 15 by ropes or flexible elements 31, secured to the apertured cleats 28 and 29, and passed about and over the boat 13 and tied to appropriate tie-points on the boat.

A keel 32 is provided, including a bow section 33 and a stern section 34, having their inner ends connected by leaf-hinges 35, so that these keel sections may be folded or collapsed, Figure 6. The keel sections 33 and 34 are provided at their tops and near their opposite ends with pairs of guide straps 36, rigidly secured thereto by bolts 37. These guide straps project above the top edges of the keel sections and are adapted to receive between them the sub-keel sections, thus securely attaching the keel sections to the sub-keel sections, in a detachable manner, as will be described. Diagonal guys or wires 38 are attached to the keel sections 33 and 34 near their bottom edges and these guys are attached to the cleats 28. The guys 38 are drawn tight by turnbuckles 39. It is thus seen that the keel is securely held in place upon the sub-keel and may be removed therefrom, when desired.

The numeral 40 designates a rudder and 41 is a tiller rod, having a horizontal extension 42. The rudder is held to the tiller rod 41 and extension 42 by straps 43. U-shaped brackets 44 are provided, having horizontal apertured extensions 45. The upper U-shaped bracket 44 engages

over the rear end of the sub-keel extension 27, and is rigidly attached thereto by bolts or the like, and this bracket also fits within a notch 46 formed in the keel section 34, Figure 6. The lower bracket 44 receives the lower edge of the keel section 34 and is secured thereto by bolts or the like. The apertured extensions 45 pivotally receive the tiller rod 41, the extensions 45 projecting into notches 47, Figure 9.

The tiller rod 41 is equipped with a tiller arm 48, which is horizontal, and carries a strap 49, receiving therein the upper horizontal extension 50 of the vertical tiller rod 41. This vertical tiller rod passes into the forked end of the tiller arm 48, and has clamping engagement with the sides of this forked end by means of a bolt 51, which draws the sides together, if desired.

The numeral 52 designates a mast, formed in upper and lower sections 53 and 54, detachably connected by a sleeve 55. The lower end of the lower section 54 is inserted within a socket 56, suitably secured to the bottom of the boat 15, adjacent to the bow. The mast is connected at its top with guys 57, extending downwardly for connection with rings 58, secured to straps 59, in turn attached to the cleats 28 and 29. The mast 52 carries a sail 60 and this sail has its top connected with a rope 61, passing over a pulley 62, and this rope 61 extends downwardly for suitable connection with the ring 72 or straps 63, suitably attached to the cleats 29. The rope 61 also serves as a guy for the mast. The sail 60 is secured to the mast 52 by loose lacing, as indicated at 64, although large rings may be employed. A boom 65 is provided, secured to the sail 60 by lacing 66. This boom has a ring 67 at one end, slideable upon the mast section 54, and held against upward movement by a pin 68. The boom swing is regulated or adjusted by a rope 69, running through pulleys 70, carried by straps 71, secured to the cleats 28 and 29, as shown.

Having thus described my invention, what I claim is:

1. A base to be mounted upon a flat bottom boat or the like, comprising flat hinged base sections, apertured cleats secured to the base sections near their marginal edges, a vertically narrow sub-keel section secured to each base section, the sub-keel sections being assembled to form a sub-keel permanently secured to the base, a keel

comprising keel sections, opposed flat plates forming sockets secured to the upper edges of the keel sections and projecting above the same for receiving the sub-keel therein, diagonal guys secured to the keel sections near their lower edges and having their opposite ends secured to certain of the cleats, a rudder pivotally mounted upon the keel, and flexible elements secured to certain of the cleats and engaging about and connected with the sides of the boat.

2. A sailing and steering attachment for flat bottom inflatable rubber boats and the like, comprising flat hinged connected base sections to be arranged against the flat bottom of the boat, apertured cleats secured to the base sections near their marginal edges, a vertically narrow sub-keel section secured to each base section, the sub-keel sections assembling to form a sub-keel permanently secured to the base sections, a keel comprising keel sections, opposed upstanding pairs of flat plates forming sockets secured to the top edges of the keel sections and projecting above the same for receiving the sub-keel therein, diagonal guys secured to the keel sections near their lower edges and having their top ends connected with certain of the apertured cleats, a steering rudder pivotally connected with the rear keel section, flexible elements secured to certain cleats and engaging about the sides of the boat and connected with the boat, a mast, a sail carried by the mast, and guys secured to the mast and extending about the sides of the boat and connected at their lower ends with certain of the cleats.

JOHN C. BOYD.
